United States Patent Office.

JOHN K. HARRIS, OF SPRINGFIELD, OHIO.

Letters Patent No. 78,282, dated May 26, 1868.

IMPROVEMENT IN HARNESS.

The Schedule referred to in these Letters Patent and making part of the same.

TO ALL WHOM IT MAY CONCERN:

Be it known that I, JOHN K. HARRIS, of Springfield, in the county of Clark, and State of Ohio, have invented a new and useful Improvement in Breast and other Collars for Horse-Harness; and I do hereby declare the following to be a full, clear, and exact description thereof, reference being had to the accompanying drawings, making part of this specification.

My invention consists principally in a new mode of constructing ordinary breast-collars or hames-tugs, so as to obtain a limited elastic draught from the same without destroying the flexibility of any of the parts; also in the arrangement of a strong stop or check to the elastic movement, whenever the elastic device is brought to a certain amount of tension, so as to prevent breakage or injury to the same by overstrain or excessive pressure. In the accompanying drawings—

Figure 1 shows one end of my flexible elastic breast-collar in connection with other parts of the harness.

Figures 2 and 3 show the construction and arrangement of the interior parts, with the outer covering removed.

Figure 4 shows the internal parts in position, with the covering removed.

Figure 5 shows the same elastic arrangement applied to an ordinary hames-tug.

Fig. 2 represents a strong flexible leather frame, composed of a piece of thick leather, A, having the upper and lower parts, $a a'$, doubled and looped around the check-bar C, the space a'' , between these parts, being open to receive the springs and flexible draught-strap, to be presently explained.

The spring-resisting cross-bar D, fig. 3, is firmly secured, at each end, to the upper and lower parts, $a a'$, of the flexible frame, by a tenon and rivet, at a suitable distance from the check-bar C, to allow the desired elastic movement of the draught-strap.

Fig. 3 represents my improved flexible draught-strap, having any desired number of strong, flexible thong or cords, X, extending from one end of the same, and passing through openings in the bar D, thence through the coil-springs M, fig. 4, each thong terminating in an enlarged head, x. These thongs may be made of raw hide, or any strong, flexible material. The main body of this flexible draught-strap B is composed of two straps of leather, stitched firmly together, with a small plug or piece of leather, $b b'$, between the same, in front and rear of the cross-bar C, leaving a space between said plugs $b b'$ sufficient for the play or elastic movement of draught-strap B. The flexible frame A, fig. 2, being secured to the breast-collar, and the draught-strap and springs being in proper position, as shown by fig. 4, the whole is enclosed by the usual folds or covering, as shown in fig. 1, presenting a neat and finished appearance, combining flexibility with elasticity. Whenever sufficient power is applied to draw out the draught-strap B, until the inner fastening, b, abuts against the check-bar C, the springs and thongs are at once relieved from any further strain, which is found to be absolutely necessary to insure their durability.

To this elastic strap, extending alike from each end of the breast-collar, I attach, by buckle, H, fig. 1, another strap, I, which extends directly back to the breeching, and is looped in a ring of the same, having an ordinary slide-buckle, for adjustment to different lengths. To this side strap, in line with the ordinary saddle-pad, I attach another short cross-strap, K, having a buckle, k, at the upper end, to connect with the ordinary saddle or shaft-bearer strap k' , and the lower end, k'' , is used for the girth or belly-band fillet.

At or near the intersection of these last-named straps, I secure a metallic plate, O, provided with a slot, o, to receive a staple, T, which is attached to the inside of shaft S, which staple is held, in connection with plate O, by the end of the shaft-bearer strap, k' , passing vertically through both staple and plate, or by the use of any other convenient leather or metallic key.

Thus it is plain that with my improved harness the horse may be conveniently and quickly attached to or detached from the vehicle, and that the ordinary traces, single-tree, shaft-tugs, or thimbles, are dispensed with, thus simplifying and reducing the cost of harness.

The elastic breast-collar is found, by practical use, to adjust itself perfectly to the right and left alternating

motion of the horse's shoulders, and being pliable as well as extensible and elastic, having all the metallic parts entirely covered and shielded from contact with the horse, prevents chafing or galling.

The springs are also found to be much more durable and reliable than they have been in the various forms heretofore used, having a leather surface, both outside and inside, to wear against, instead of a metallic surface, and also having a reliable check to over-tension.

It is evident, from fig. 5, that the same flexible, elastic arrangement herein shown and described, and embraced in the construction of a breast-collar, may be applied and used in a hames-tug, or a harness with hames, as well.

I am aware that an elastic feature in a trace-dispensing harness is not new, being embraced in a patent granted to H. C. Smith, July 10, 1866, and now wholly assigned to me; also in patents heretofore granted to myself; but in all these the elastic device is combined with and obtained from the parts which attach to the shafts, called a "buckle," "hitching device," "draught-plate," &c., necessarily making these parts too large, rigid, and heavy for light harness; besides, being exposed between the shaft and horse, they are liable to injure him by constant rubbing and chafing; and as there has usually been no provision of a check to the springs, as a safeguard against sudden strains or over-tension, they are liable to break, or to become permanently closed.

I do not, therefore, claim as new any elastic device, when the same is embraced in or derived from any of the metallic parts which are to be attached to the shafts. Neither do I claim any "hitching-device" consisting of a "link," draught-plate, tubular frame, or any other device to be attached to the shafts, when the elastic draught is obtained directly from the same; but

What I do claim as new, and desire to secure by Letters Patent, is—

1. The provision, in a breast-collar or hames-strap, of the flexible, extensible, and elastic device X & M, the same being provided with check-pieces b b', C D, substantially as and for the purposes herein explained.
2. The arrangement of draught-strap B, open leather frame or breast-strap A, thongs X, spiral springs M, and check-pieces b b', C D, as and for the purpose specified.

In testimony of which invention, I hereunto set my hand.

JOHN K. HARRIS.
